US0D1071412S

(12) **United States Design Patent** (10) **Patent No.:** **US D1,071,412 S**
Chen (45) **Date of Patent:** **** Apr. 15, 2025**

(54) **AUTOMATIC CLEANING ROBOT FOR SWIMMING POOL**

(71) Applicant: **Hangzhou Maichi Chushi Purifying Equipment Co., Ltd.**, Hangzhou (CN)

(72) Inventor: **Jie Chen**, Hangzhou (CN)

(73) Assignee: **Hangzhou Maichi Chushi Purifying Equipment Co., Ltd.**, Hangzhou (CN)

(**) Term: **15 Years**

(21) Appl. No.: **35/518,547**

(22) Filed: **Sep. 1, 2023**

(80) **Hague Agreement Data**

Int. Filing Date: **Sep. 1, 2023**

Int. Reg. No.: **DM/231795**

Int. Reg. Date: **Sep. 1, 2023**

Int. Reg. Pub. Date: **Oct. 6, 2023**

(30) **Foreign Application Priority Data**

Aug. 1, 2023 (CN) 2023304854010.0
